ALIGNMENT CONTROLLING PACKAGING MACHINE

Leroy L. Salfisberg, South Orange, N. J., assignor
to Ivers-Lee Company, Newark, N. J., a corporation of Delaware

Application January 16, 1946, Serial No. 641,569

7 Claims. (Cl. 93—3)

1

This invention relates in general to methods of and machines for packaging commodities, such as tablets, pellets, powdered or granular substances, etc., wherein layers or strips of packaging material are continuously fed into juxtaposition, the material to be packaged is deposited between the layers, and the layers then are sealed around the commodity to form a compartment in which the commodity is encased, thereby forming a strip or chain of packages which later can be severed singly or in groups.

In many instances one of such layers or strips bears indicia, such as printed matter, a zone of color, a particular design, or the like for each compartment, which it is desired to locate in a predetermined relation to the corresponding compartment, for example in alignment or in register with the compartment. However, with the present packaging machines due to slippage or stretching of the strips of packaging material or other causes, said indicia bearing zones get out of register with the respective compartments, which detracts from the appearance of and may spoil the package.

One object of this invention is to provide a novel and improved method of and machine for periodically registering or compensating for mis-register of said indicia-bearing zones with their respective compartments.

A specific object is to provide novel and improved manually actuated means for controlling the feeding movement of the packaging material.

Another object is to provide apparatus of this kind that is simple in construction, inexpensive to manufacture and highly efficient in operation.

Other objects, advantages and results of the invention, will be apparent from the following description of the invention in conjunction with the accompanying drawing in which

Figure 1 is a fragmentary top plan view of packaging apparatus embodying my invention.

Figure 2 is a sectional view of the rollers shown in Figure 1 with the strips of packaging material in normal position therebetween.

Figure 3 is a view similar to Figure 2 but showing the strips being operated upon by the alignment restoring devices.

Figure 4 is a sectional view showing the strip aligning devices in normal or neutral position.

Figure 5 is a view similar to Figure 4 but showing the strip aligning devices moved to an adjusting position.

Figure 6 is a fragmentary top plan view of a strip in proper aligned position with the article receiving recess in the roller, and

2

Figure 7 is a view similar to Figure 6 but showing the strip out of alignment with the recess.

Specifically describing the illustrated embodiment of the invention, strips 1 and 2 of packaging material are fed from any suitable supply of such material. The strip material may consist of chlorinated rubber otherwise known as "cellophane" or other suitable materials.

The strips pass over idler rollers 3 and 4 past an article feed and depositing mechanism, for example, such as shown in my Patent No. 2,083,617 or my copending application Serial No. 560,306, filed October 25, 1944, now Patent No. 2,420,982, issued May 20, 1947, including a chute 5 to a crimping and sealing mechanism which includes rollers 6 and 7 which frictionally contact with and receive the strips between them. The rollers 6 and 7 are mounted on and rotated in opposite directions by shafts 8 and 9, respectively, journaled in frame members 10 and 11 and are driven by intermeshing gears 12 from any suitable source of power. The rollers have complementary registering recesses 13 to provide clearance between them for the tablets 14 between the strips 1 and 2, the recesses being spaced circumferentially of the rollers. The rollers may have their peripheries between the recesses and on the sides thereof roughened or serrated as shown in my Patent No. 2,083,617 for transversely crimping or corrugating and pressing together the strips between adjacent articles and along the edges for encasing the tablets and forming the units 15.

One of the strips, for instance, the strip 1 is provided on its surface with spaced indicia bearing portions 16 adapted to form one wall of the unit 15 containing the tablet. Such indicia bearing portions are spaced apart a distance corresponding to the distance between the recesses in the roller 6.

The tablets are fed periodically and the rollers are rotated in timed relationship with respect to the movements of the strips and the tablets and with respect to each other in a manner such that the recesses coincide with each other as the rollers are rotated in opposite directions and so that normally a tablet and an indicia bearing portion of strip 1 are simultaneously received in register with each other between the coinciding recesses.

The present invention contemplates mechanism for restoring the indicia bearing portion of the strip 1 to proper relationship or alignment with the tablet received between the recesses in case said portion gets out of alignment with said tablet as shown in Figure 7. Referring to Figures 1, 2 and 3, between the recesses 13 of roller 7, the

periphery of said roller has transverse slots 17, the base of each slot being straight. The periphery of roller 6 is likewise formed with transverse grooves 18 between the recesses formed thereon. The base of each groove is tapered as shown in Figures 4 and 5. Slidably mounted in each groove 18 is a blade or plate 19. The blade projects beyond the ends of the roller and is substantially triangular in shape with a straight rounded outer edge 20 and a flat tapered inner edge 21 slidable on the tapered base of the groove. The broader end of the blade is notched to form a hook 22.

The mechanism for actuating the blades comprises a disc 23 slidably mounted on shaft 8, the periphery of which is positioned in the hooked portions 22 of the blades. The blades are yieldingly held on the disc and roller by means of coiled springs 24 encircling the projecting ends of the blades and positioned in grooves in the outer edges of the blades. Disc 23 has a hub 25 with a circumferential groove 26 adapted to receive the bifurcated end 27 of a yoke member 28, the other end of said yoke member being secured to a shaft 29 rotatably and slidably mounted between the frame members 10 and 11 parallel to the shaft 8. One end of the shaft 29 is screw threaded as at 30 and extends loosely through the frame member 11 to the outside thereof. Supported on the outside of said frame member 11 by a bracket 31 is a knurled nut 32. Turning of the nut will cause rotation and sliding movement of shaft 29 carrying the yoke member 28 along with it which will slide the disc 23 along shaft 8 thereby moving the blades along the grooves and radially of the roller 6 as shown in Figures 4 and 5.

In operating the machine, the blades are positioned with their narrow ends in the grooves so that their outer edges normally project a short distance outwardly beyond the periphery of the roller 6, which is the neutral position. When the operator discovers that the indicia bearing portions of the strip 1 have become out of alignment in one direction or the other with the coinciding recesses in the rollers 6 and 7 as shown in Figure 7, the proper alignment may be restored by turning the nut 32 in the proper direction to move the shaft 29 and thereby move the blades along the grooves 18 and radially outwardly or inwardly of the roller 6 as may be required toward the positions shown in Figure 2 or 3. As the grooves 18 coincide with the slots 17, upon rotation of the rollers 6 and 7, the radial movements of the blades will press or bend the overlapping strips 1 and 2 into the registering slot 17 in a loop formation as shown in Figure 3 thereby pulling down more or less on the strips and varying the feed of the strips. This variation may be continued until it is observed that the indicia bearing portions are restored to proper alignment with the recesses in the rollers at which time the shaft 29 is moved back again to return the blades to their normal or neutral position.

Changes and modifications may be made in the method and the machine without departing from the spirit or scope of the invention. Also it will be understood that the structure of the package may be widely modified, for example instead of using two strips of packaging material, a single strip folded longitudinally to produce a plurality of layers could be utilized. Furthermore, one of the layers might be opaque while the other is transparent, and the indicia may be placed on either the transparent layer or on the opaque layer to be visible through the transparent layer. Moreover, suitable automatic means such as

photo-electric mechanism may be utilized for actuating the means for adjusting the layers of packaging material.

What I claim is:

1. A packaging machine including the combination with means for periodically feeding portions of a commodity, of a pair of rotatable rollers to receive between them opposed layers of packaging material at least one of which has indicia-bearing zones and between which each of said commodity portions is deposited normally in register with one of said indicia-bearing zones, and means on said rollers for adjusting said layers of packaging material to vary the relationship of said indicia-bearing zones to the respective commodity portions, and means for rotating said rollers simultaneously in opposite directions.
2. A packaging machine including the combination with means for periodically feeding portions of a commodity, of a pair of rotatable rollers to receive between them opposed layers of packaging material at least one of which has indicia-bearing zones and between which each of said commodity portions is deposited normally in register with one of said indicia-bearing zones, one of said rollers having a plurality of longitudinal slots spaced circumferentially thereof, and the other roller having a plurality of radially adjustable blades, one to enter each of said slots as said rollers rotate for pressing said layers of packaging material into said slots, whereby to adjust said layers to vary the relationship of said indicia-bearing zones to the respective commodity portions.
3. The packaging machine as defined in claim 2 with the addition of means for moving said blades including a slideable disc coaxial with the last-named roller, a yoke member having one end connected to said disc and its other end connected to a screw threaded shaft, and an actuating nut on one end of said shaft for moving the same.
4. In a packaging machine, means for feeding a commodity, a pair of opposed parallel rotatable rollers for feeding between them strips of packaging material one of which has spaced indicia-bearing portions on its surface on opposite sides of said commodity in predetermined relationship with certain circumferentially spaced zones on the peripheries of the rollers, and means for restoring said predetermined relationship in case said relationship is disturbed including members to bend said strips laterally during their feeding movement.
5. In a packaging machine, means for supplying layers of packaging material in spaced opposed relation to each other, means for periodically depositing material to be packaged between said layers, means for sealing said layers together to encase said material and for feeding said layers including a pair of opposed parallel rotatable rollers to receive between them said layers having the material between them, and manually actuated means for adjusting the relationship of said layers and the peripheries of said rollers including blades carried by one of said rollers adapted to press against said layers during their movement.
6. In a packaging machine, means for periodically feeding a commodity, means including opposed parallel rotatable rollers for automatically feeding between them strips of packaging material one of which has spaced indicia-bearing portions on its surface on opposite sides of said commodity feeding line in predetermined re-

lationship with certain circumferentially spaced zones on the peripheries of the rollers, and manually actuated means for restoring said predetermined relationship in case said relationship is disturbed including blade members adapted to press against the strips during their feeding movement.

7. The packaging machine as defined in claim 5 wherein the other of said rollers has longitudinal slots spaced circumferentially of the roller, one for each of said blades so that said

blades press said strips in the corresponding slots as said rollers rotate.
